Primary Examiner — Deanna L Pratt*(74) Attorney, Agent, or Firm* — Weide & Miller, Ltd.

(57) **CLAIM**

The ornamental design for multi-functional electrician pliers, as shown and described.

DESCRIPTION

FIG. 1 is a front, left perspective view showing multi-functional electrician pliers.

FIG. 2 is a rear, right perspective view of the multi-functional electrician pliers of FIG. 1.

FIG. 3 is a top view of the multi-functional electrician pliers of FIG. 1.

FIG. 4 is a front view of the multi-functional electrician pliers of FIG. 1.

FIG. 5 is a bottom view of the multi-functional electrician pliers of FIG. 1.

FIG. 6 is a rear view of the multi-functional electrician pliers of FIG. 1.

FIG. 7 is a left-side view of the multi-functional electrician pliers of FIG. 1; and,

FIG. 8 is a right-side view of the multi-functional electrician pliers of FIG. 1.

The broken lines illustrate portions of the multi-functional electrician pliers that form no part of the claimed design.

1 Claim, 4 Drawing Sheets
